(57) **CLAIM**

The ornamental design for a fairing with flow channels, as shown and described.

DESCRIPTION

FIG. 1 is a top, front, left perspective view of a fairing with flow channels according to my new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The dashed line portion of the drawings is included to show unclaimed subject matter only for the purpose of illustrating environment and forms no part of the claimed design. The dash-dot-dot line portions in the drawings define a boundary of the claimed design and form no part thereof
